KNITTING MACHINE

Max C. Miller, Cumberland, R. I., assignor to
 Knitting Machine Corporation, a corporation of
 Delaware

Application May 29, 1937, Serial No. 145,498

39 Claims. (Cl. 66—96)

The present invention relates to improvements in welt mechanism for flat knitting machines, and more particularly to improvements in take-up mechanism for engaging with and tensioning the fold of welt fabric away from the needles.

The invention is herein disclosed in a preferred form as embodied in a full-fashioned machine having automatic devices for setting up an initial course of welt fabric, and for thereafter turning the welt, together with take-up mechanism including a welt wire for each knitting section and take-up devices associated therewith which are automatically tripped into active operation prior to the turning of the welt. With this construction and arrangement of the welt turning mechanism, it is necessary for the operator to lay in the welt wires and attach them to the usual fabric take-up straps after commencing the new set. Experience has shown that in the operation of high speed full-fashioned machines of either the single or multiple section type in which the operator has the care of a relatively large number of knitting sections, the operator has not a sufficient amount of time in which to lay in the welt wires and to attach the usual fabric take-ups thereto during the knitting of the initial courses of the welt fabric, with the result that the machine must be stopped or an assistant employed to assist in this operation.

It is a principal object of the present invention to provide novel and improved welt fabric take-up mechanism including supporting and actuating means for the take-up wires constructed and arranged for fully automatic operation to engage with and take up the knitted fabric without the necessity of any particular attention on the part of the operator after the commencing of the new set.

It is more specifically an object of the present invention to provide mechanism for laying in and supporting the welt wires which will enable these wires to be placed in position during the knitting of a previous set at some stage in the operation when more time is available, and thereafter to be operatively connected with fabric take-up means operating in the usual manner to tension the fabric away from the needles.

It is a further object of the invention to provide supporting and actuating devices for the welt wires and the take-up means associated therewith, constructed and arranged for automatic operation to engage the take-up means with and to move the welt wires into active operation during the knitting of the welt fabric.

With these and other objects in view, as may

hereinafter appear, the several features of the invention consist also in the devices, combinations and arrangement of parts which together with the advantages to be obtained thereby will be readily understood by one skilled in the art from the following description taken in connection with the accompanying drawings, in which Fig. 1 is a partial view in front elevation of a flat full-fashioned knitting machine, only so much of the machine being shown as is believed necessary to illustrate the connection of the present invention therewith; Fig. 2 is a sectional view taken on the line 2—2 of Fig. 1; Fig. 3 is an enlarged detail view of the hook portion of the wire pendant take-up illustrated in Fig. 2; Fig. 4 is a detail view of the parts shown in Fig. 3 looking from the left; Fig. 5 is an enlarged detail view of the picot bar and welt wire support secured thereto; Fig. 6 is a detail plan view illustrating substantially the parts shown in Fig. 5; Fig. 7 is a detail view in front elevation of portions of the fabric take-up mechanism illustrated in Fig. 2; and Figs. 8 to 14 inclusive, are a series of partial views on an enlarged scale looking from the left, illustrating particularly the relative positions of the needles, the narrowing machine including the picot bar and welt wire support and welt wire take-up, during the successive stages of the operation to engage the take-up with and move the welt wire into engagement with the welt fabric.

The machine disclosed in the drawings comprises a flat full-fashioned multiple section knitting machine which may be of ordinary description, and is provided with an automatic welt turning mechanism which is substantially identical except as hereinafter set forth, with that set forth in applicant's copending application Serial No. 726,285, filed May 18, 1934. The knitting instrumentalities of the machine, as best shown in Figs. 1 and 2, include a series of spring beard needles 20 for each knitting section, supported on needle bars 22 for movement with relation to a fixed press edge formed on the sinker bed 24, knockovers 26 and yarn measuring sinkers 28. The machine is also provided with the usual narrowing machine frame including the vertically movable narrowing machine support bar 30 having secured thereto brackets 32 for the narrowing point rods 34 and narrowing point units 36. There is also provided with each section of the machine, a picot bar 38 carrying picot points 40 and rotatably mounted on a picot rod 42 which is supported in the usual manner in brackets (not shown) for vertical movement with the narrowing machine support rod 30. The

work table of the machine is shown at 44 mounted on the usual transverse machine frame members 46.

The welt turning mechanism for the machine, 5 comprises a welt hook bar 50 for each section of the machine, having vertically arranged welt hooks 52, and supported for movement toward and away from the needles on a pendant 54 which is pivotally supported above the needles on a 10 pivot shaft 56. The shaft 56 is in turn supported for vertical movement on supporting lever arms 58 mounted to turn on a shaft 60. For supporting certain operating mechanisms of the machine, and more particularly the welt shaft 56, upward- 15 extending brackets 62 are provided at spaced intervals along the machine length rigidly mounted at their lower ends on the work table 44. Inasmuch as these mechanisms as thus far described, are fully illustrated and described in applicant's copending application above referred to, and form specifically no part of the present invention, no further description or illustration thereof is believed necessary.

In carrying out the present invention, a fabric 25 take-up mechanism is provided having a number of novel features of construction and mode of operation to enable the welt wires to be laid into the machine prior to the commencing of a new set, and subsequently to be brought into active 30 operation automatically during the knitting of the welt fabric to engage with and take up the fold of welt fabric. The instrumentalities employed for these purposes in the preferred form 35 of the invention illustrated, comprise supporting means for the welt wires constructed and arranged to support the welt wires in a position which will not interfere with the operation of the various knitting instrumentalities of the machine including the pendant welt bar, above described, and an auxiliary fabric take-up device 40 which is constructed and arranged to engage with and move the welt wires away from their supports to engage with and tension the fold of welt fabric 45 away from the needles, and subsequently after the knitting of a sufficient amount of additional fabric, to cause the welt wires and fabric engaged thereby to be operatively connected with and wound upon the usual fabric take-up rolls of the machine. The auxiliary take-up, having 50 delivered the welt wires and fabric supported thereon to the fabric rollers, may then be returned to inoperative position and can be utilized in the knitting of the next succeeding set without any necessity on the part of the operator for first 55 clearing the fabric take-up rollers of the previously cast-off set. To further facilitate in the operation of the device, it is contemplated that a spare set of welt wires will be employed which may be laid in on their supports during the latter stages of the knitting of the set and before 60 the welt wires utilized in knitting the previous set are removed from the machine.

In accordance with one feature of the invention, supporting means are provided for the welt 65 wires, constructed and arranged to permit the laying in of the welt wires on their supports during the knitting of a previous set, in such a position that they will not interfere in any way with the operation of the various cooperating mechanisms of the machine, and may subsequently be brought into active operation during the knitting of the welt fabric, without the necessity of further individual attention on the part of the operator.

75 As best shown in Figs. 2, 5 and 6 of the draw-

ings, two welt wire supporting brackets 70 are rigidly secured to each picot bar 38, one being mounted adjacent each end of the bar. The brackets 70 are provided with recesses 72 to receive the welt wire 74 which is provided adjacent 5 each end thereof with a reduced portion in the form of an annular groove 76 arranged to fit within the recess 72. The brackets 70 are mounted in an inverted position on the outer or forward face of the picot bar 38, so that when the picot bars 38 are swung upwardly to their inoperative position, the open ends of the recess 72 will face upwardly to permit the operator conveniently to drop the welt wire into its holder. Each of the brackets 70 is slotted to receive a spring lock 10 latch 78 pivotally supported on a pin 80, and provided with a V-shaped cam surface arranged to project across the slot 72. A small compression spring 82 seated in a recess in the bracket 70, tends to maintain the latch 78 in a fully advanced 15 position against a stop pin 84 to prevent the falling out of the welt wire 74 when the picot bar 38 with the brackets 70 is swung forwardly and down to its operative position. With this construction and arrangement of the welt wire support, it will readily be seen that the welt wire 74 may be laid into its holders 72 at any time during the knitting of the previous set after the picot bar 38 has been raised to its inoperative position, and while so supported, will not interfere with the operation of the various cooperating mechanisms of the machine, and more particularly with the movement of the welt bar 50 and pendant 54 to engage with and remove from the needles the initial course of welt fabric. When the picot bars 38 are now swung downwardly to their operative positions in the usual manner for the knitting of the picot or halfway special welt course, the welt wires are at the same time moved into position for subsequent engagement by the take-up, as hereinafter more fully set forth.

The fabric take-up mechanism illustrated as embodying in a preferred form certain features of applicant's invention, comprises the usual fabric take-up rollers 90, one being provided for each knitting section of the machine rigidly secured to a take-up shaft 92 rotatably mounted in stationary brackets 94 on the transverse frames 46. The shaft 92 may be tensioned by any convenient means as, for instance, by means of weights 91, take-up strap 93 and pulley 95, connected to turn with shaft 92 by pawl 97 and ratchet 99 (see Fig. 1), to impart a rotatable take-up tensioning strain to the fabric take-up rollers 90.

In accordance with one feature of the invention, a novel take-up device is employed to engage with and tension the welt wires 74 against the fabric, and thereafter to cause the welt wires and fabric attached thereto, to be connected with and rolled onto the take-up rollers 90. The welt wire take-up, as best shown in Figs. 1 and 2, comprises a pair of resilient wire pendants 96 for each knitting section, which are rigidly secured at their upper ends to a welt wire take-up shaft 98 supported at intervals along the length of the machine by extension brackets 100 adjustably supported on a fixed shaft 102 mounted on the overhead brackets 62. Each of the wire pendants 96 is adjacent its lower end sloped 65 rearwardly and has pivotally mounted thereon a spring-pressed hook 104 which is adapted for engagement with the adjacent end of the welt wire 74 as hereinafter more fully set forth. The lower end of each wire pendant 96 is slotted to 70

75

receive a hook 104 which is provided with a tail which is held yieldingly in position against a stop pin 108 by means of a small tension spring 110 connected between the tail of the hook 104 and a bracket 112 on the wire pendant 96. The bracket 112 also carries a pivot pin 114 which provides a pivotal support for a locking latch member 116 having a curved contact surface 118 for engagement with the welt wires 74. The latch member 116 is held yieldingly in operative position by means of a small compression spring 120 seated in a recess formed in the wire pendant 96. For controlling the operation of the wire pendants 96, there is secured to the rock shaft 98, a downwardly extending arm 124 which is tensioned forwardly by means of a take-up strap 126 passing over an idler roller 128, being connected at one end to the arm 124, and at its other end to a weight 129.

20 The wire pendants 96 are constructed and arranged to be moved rearwardly and to be supported in close proximity to the needles for engagement with the welt wires 74 by means of a latch mechanism which comprises a latch lever 130 pivotally supported on a bracket 132 secured to the adjustable supporting arm 100, and is provided at its forward end with a hook arranged for engagement with a lug 134 on the lever arm 124. At its rear end the latch lever 130 is provided with a pin 136 for engagement within a slot formed by the looped upper end of a link 138. The link 138 extends downwardly through an aperture formed in the usual picot cover plate 140, and has screw-threaded to its lower end an adjustable lock nut 142 which is arranged during the downward movement of the narrowing machine in forming the picot, to engage against the under side of the cover plate 140 to release the latch and permit the movement of the pendant take-up members 96 away from the needles, as more fully set forth in connection with the following description of the operation of the device. A tension spring 144 secured at one end to the bracket 132 and at its other end to a collar 146 on the link 138, tends to swing the latch lever 130 in a clockwise direction as shown in Fig. 2, into latching position, this movement being limited by the engagement of a stop screw 148 on the latch lever, with a forward extension of the bracket 132.

Further in accordance with the present invention, mechanism is provided which is rendered operative during the continued knitting of the stocking blank, to disconnect the welt wires 74 and fabric held thereon, from the pendant take-ups 96, and to cause the fabric to be engaged with and rolled onto the usual take-up rollers 90. To this end, a hook-shaped grab 150 is rigidly secured to each end of the take-up roller 90 associated with each knitting section to engage with and receive the welt wire 74 from the pendant take-up hooks 104. The take-up roller shaft 92 and rollers 90 with the grabs 150, are normally held in a predetermined angular position against the pressure of the usual take-up straps and weights associated therewith, by means of a latch mechanism which is arranged to be tripped by the forward movement of the control lever 124 when the knitting of the fabric has progressed far enough to bring the welt wires 74 supported by the pendant take-ups into position to be engaged by the grabs. This trip mechanism comprises an upwardly extending lever 152 which is pivoted at its lower end on a pin 154 on a stationary bracket 156, and at its upper end

carries a stop screw 158 for engagement with the control lever 124. The lever 152 is provided adjacent the hub portion thereof, with a lug 160 for engagement with a notched tail portion 162 formed on one of the grabs 150. A torsion spring 164 coiled about the pivot pin 154 and secured at one end to a collar 166 thereon (see Fig. 1), and at its other end to the hub of the latch lever 152, tends normally to maintain the lever in latching position. A stop screw 168 supported on an arm of the latch lever 152 is arranged for engagement against the sleeve hub for the idler roller 128 to limit the rearward movement of the latch lever 152 under the pressure of its spring. The forward movement of the pendant take-ups 96 and lever arm 124 under the influence of the take-up strap 126, is limited by the engagement of the lever arm 124 with a stop screw 170 supported on an upward extension 172 of the stationary bracket 156.

The operation may be briefly described as follows:

Let us assume that the fabric has been pressed off and that it is wound around the fabric rolls 90 in the ordinary manner. During this time the counterweight take-up pendant lever 124 and the pendant take-ups 96 are in the position shown in dot-and-dash lines, Fig. 2, with the grabs 150 not in their locked position as shown in solid lines in Fig. 2, by reason of the fact that the upper screw 158 of the lever 152 is in contact with the lever 124. The spare set of welt wires 74, at this time, are all in position in their supports 72. The machine is stopped at this time and without taking the previous set of fabrics off their respective rolls 90, the operator prepares the turned welt mechanism for action, as described in the copending welt application. The pendant take-ups 96 and lever or levers 124 are now swung forward manually into their solid line position, Fig. 2, where they are locked in position by the latch or latches 130. The take-up rollers 90 and grabs 150 secured thereto, are now turned to the solid line position shown in Fig. 2, in which they are held by the engagement of the lug 160 on latch lever 152 with the notched tail 162. The machine is now put into power operation, the welt pendants functioning as described in the copending application, to form the fabric set-up and to take up the fabric as it is knitted. After a short length of welt fabric has been formed and before it is necessary to form the picot or half-way special welt course, the operator, following the customary procedure in full-fashioned machines, manually turns down the picot bar to the position shown in Fig. 9. At the proper time the pattern chain of the machine then causes the narrowing machine on which the picot bar is supported, to move downward to commence the forming of the picot course. As the narrowing machine makes this downward movement, the welt wires 74 engage the rearwardly sloping lower ends of the pendant take-ups 96 as shown in Fig. 10. As these wires are flexible, they will, upon continued downward movement of the narrowing machine and welt wires 74, be forced outwardly in the direction of the arrow, Fig. 10, so that the welt wires will engage with and fold upwardly the hooks 104 against the pull of their springs 110, illustrated in Fig. 3, and so snap by the lower end of these hooks allowing the take-ups 96 to return again into the position shown in Fig. 11. During this first or loop taking down movement, the narrowing machine does not move downwardly far

enough to engage stop nut 142 on the link 138 with the guard rail 140, and so does not actuate and disengage the latch 130 from the lug 134 of the lever 124, Fig. 2. The narrowing machine 5 then lifts from the Fig. 11 position to a position where the welt wires almost contact the lower surface of the latches 116, but without any effect thereon. In this intermediate position, the narrowing machine rests a moment as is customary 10 to permit a lateral movement of the picot point bars before the narrowing machine continues its second and more extended downward movement, which movement now causes the guard rail 140 to engage with and depress the stop nut 142 and link 138, to disengage the latch 130 from the lug 134, thereby permitting the welt wires 74 to be 15 acted upon by the take-up cord 126, in this manner positioning the hooks 104 against the welt wires 74, as shown in Fig. 12. Continued upward movement of the narrowing machine incidental to the transfer of the loops now on the picot points to the needles, causes the welt wires 74 to assume the position shown in Fig. 13, the latches 116 spring-seatedly holding them in this 20 position while the continued upward movement of the narrowing machine causes the welt wires to snap out of their supporting slots 72 past the spring-seated lock latches 78. The welt wires now assume the position shown in Fig. 14, to engage with and tension the fabric beneath the welt hooks 52. This doubling of the welt fabric and the taking over of the fabric take-up action by the welt wires 74, takes place before the welt pendants have reached the end of their outward 25 or fabric take-up movement, so that, for at least some few courses, the welt hooks 52 and the welt wires 74 both act to take up the fabric. Shortly thereafter, the welt hooks reach the end of their outward movement and the welt wires 30 74 alone take over the action of taking up the fabric.

As in ordinary practice, the operator, after forming the picot course just described, manually turns up the picot bars into the position 35 shown in Fig. 2, doing this at any time during the knitting of the leg but before the first narrowing machine leg shaping movement. After they have been so turned up, the operator, manually and while the machine is knitting, lays 40 into the supporting slots 72, a spare set of welt wires 74 which are the wires that are going to be used in the next set. These welt wires 74 will 45 in no way interfere with the ordinary motion of the narrowing machine, as the picot bars 50 which support them will not be turned down again until the next set.

When sufficient fabric has been knitted, the 55 pendant take-ups 96 and the take-up arm or arms 124 will reach the position shown in dot-and-dash lines in Fig. 2, in which they have just started to contact the upper adjusting screw of the latch lever 152. As more fabric is knitted, the lever 124 acts against the latch lever 152 to 60 disengage the lug 160 from the tail 162 of the grab 150, so that the regular fabric take-up counterweight, not shown, is permitted to turn the take-up rolls 90 in a clockwise direction (see Fig. 2), thereby causing all the grabs 150 to assume the dot-and-dash position shown in Fig. 70 65. These grabs 150 engage with the take-up wires 74, and as the pendant take-ups 96 continue to take up the fabric, cause the take-up wires 74 to be cammed out of their hooks 104 and spring-pressed lock latches 116 at about the 75 time the welt wires are immediately above the

axes of the take-up rolls 90, the inner curve of the grabs 150 being so formed as to gradually bring the welt wires and fabric in contact with the outer circumference of the fabric rolls 90. The pendant take-ups 96 released from engagement with the welt wires 74, move outwardly to an inoperative position determined by the engagement of the lever arm 124 with the stop 158, as shown in dot-and-dash lines in Fig. 2. The fabric during continued knitting is wrapped 10 around take-up rolls 90 as in ordinary practice.

It will be understood that the invention is not limited to the specific embodiment shown, and that various deviations may be made therefrom without departing from the spirit and scope of 15 the appended claims.

What is claimed is:

1. In a flat knitting machine having welt turning mechanism associated therewith, the combination with a welt wire, of a support on which 20 the welt wire is located in position for subsequent engagement with the welt fabric, a fabric take-up, and means for imparting positioning movement to the take-up and to the support to operatively connect the take-up with the welt 25 wire.

2. In a flat knitting machine having a welt turning mechanism, the combination with a welt wire, of a support for the welt wire, fabric take-up means including hook elements for engaging 30 the welt wire, and means for imparting relative positioning movement to the take-up means and support to engage the hooks with the welt wire while held on said support and for thereafter moving the welt wire to take up the fabric. 35

3. In a flat knitting machine having a narrowing frame and welt turning mechanism associated therewith, the combination with a welt wire, of a support for the welt wire on the narrowing frame, a fabric take-up, and supporting 40 means on which the take-up is movable to engage with and draw the welt wire against the welt portion of the fabric.

4. In a flat knitting machine having a narrowing frame and welt turning mechanism associated therewith, the combination with a welt wire, of a support for the welt wire on the narrowing frame, a fabric take-up, and means for imparting relative positioning movements to the narrowing frame and take-up to operatively connect 45 the take-up with the welt wire. 50

5. In a flat knitting machine having a series of needles and cooperating knitting elements including a narrowing frame and welt turning mechanism associated therewith, the combination of a picot bar, pivotal supporting means on the narrowing frame on which the picot bar is movable into and out of operative position, a welt wire, and a welt wire support mounted to move 55 as a unit with the picot bar. 60

6. In a flat knitting machine having a series of needles and cooperating knitting elements including a narrowing frame and welt turning mechanism associated therewith, the combination of a picot bar, pivotal supporting means on the narrowing frame on which the picot bar is movable into and out of operative position, a welt wire, and a welt wire support on the picot bar comprising holders and latches associated there- 65 with for positioning the welt wires. 70

7. In a flat knitting machine having a series of needles and cooperating knitting elements including a narrowing frame and welt turning mechanism associated therewith, the combination of a picot bar, pivotal supporting means on the nar- 75

rowing frame on which the picot bar is movable into and out of operative position, a welt wire, and a welt wire support comprising holders supported integrally with the picot bar slotted to receive a welt wire and spring latches for retaining the welt wires in the recesses.

8. In a flat knitting machine having a series of needles and cooperating knitting elements including a narrowing frame and welt turning mechanism associated therewith, the combination of a picot bar supported for movement on the frame into and out of operative position, a welt wire, a support mounted on the picot bar on which the welt wire is located for subsequent engagement with the welt fabric, a fabric take-up, and a take-up support on which the take-up is movable to engage with and draw the welt wire against the welt portion of the fabric.

9. In a flat knitting machine having a series of needles and cooperating knitting elements including a narrowing frame and welt turning mechanism associated therewith, the combination of a picot bar supported for movement on the frame into and out of operative position, a welt wire, a welt wire support movable with the picot bar, fabric take-up means including hook elements for engaging the welt wire, and supporting and guiding means for the take-up arranged for the operative position of the picot bar and welt wire support to engage the hooks with and move the welt wire against the welt portion of the fabric.

10. In a flat knitting machine having a series of needles and cooperating knitting elements including a narrowing frame and welt turning mechanism associated therewith, the combination of a picot bar pivotally mounted on the frame for movement into and out of operative position, a welt wire, a support for the welt wire movable with the picot bar and arranged for the operative position of the bar to position the welt wire on that side of the welt bar remote from the needle series, fabric take-up means including hook elements for engaging the welt wire, and supporting and guiding means for the take-up arranged for the operative position of the picot bar and welt wire support to engage the hooks with and move the welt wire against the welt portion of the fabric.

11. In a flat knitting machine having welt turning mechanism associated therewith, the combination with a welt wire, of a support on which the welt wire is located for subsequent engagement with the welt fabric, a fabric roller take-up, intervening take-up means including welt wire engaging members, actuating means for operatively connecting said intervening take-up to tension the welt wire against the fabric, and means for automatically transferring the welt wire and fabric engaged thereby from said intervening take-up welt wire engaging members to the fabric roller take-up.

12. In a flat knitting machine having a series of needles and welt turning mechanism associated therewith, the combination with a welt wire, of a support on which the welt wire is located in position for subsequent engagement with the welt fabric, a pendant fabric take-up comprising a pivotal support located above the needles, resilient take-up members supported therefrom arranged for engagement with the welt wire, tensioning means acting on said members to take up the fabric, a fabric roller take-up, grabs associated therewith to engage with and transfer the welt wire from the pendant take-up to said roller take-up, tensioning means for said roller take-up,

a latch for locking the roller take-up out of operation, and connections actuated from said pendant take-up to release the latch.

13. In a flat knitting machine having welt turning mechanism associated therewith, the combination with instrumentalities for setting up and for taking up the welt fabric as knitted, a main fabric take-up, an intermediate take-up arranged to take up a fold of welt fabric, means for rendering said intermediate take-up operative and said instrumentalities inoperative to take up the fabric, and means for rendering said intermediate take-up inoperative and said main take-up operative to continue said fabric take-up action.

14. In a flat knitting machine having welt turning mechanism associated therewith, the combination with instrumentalities for setting up and for taking up the welt fabric as knitted, a main fabric take-up, an intermediate fabric take-up arranged to take up a fold of welt fabric, means acting to render said intermediate take-up operative during the continued take-up action of said instrumentalities, and means for rendering said intermediate take-up inoperative and said main take-up operative to continue said fabric take-up action.

15. In a flat knitting machine having welt turning mechanism associated therewith, the combination with instrumentalities for setting up and taking up the welt fabric as knitted, a welt wire, an intermediate fabric take-up connectible with the welt wire to take up a fold of welt fabric, a main fabric take-up, and means for rendering said intervening take-up inoperative and said main take-up operative to take up the welt wire and fabric attached thereto.

16. In a multiple section flat full-fashioned knitting machine having a welt turning mechanism associated therewith, the combination with instrumentalities for setting up and taking up the welt fabric as knitted, a welt wire for each knitting section, an intermediate fabric take-up for each section connectible with the welt wire to take up a fold of welt fabric, a main fabric take-up for each section, and means for rendering said intermediate take-ups simultaneously inoperative and for rendering said main take-ups simultaneously operative to take up the welt wires and fabrics attached thereto.

17. In a flat knitting machine having welt turning mechanism associated therewith, the combination with instrumentalities for setting up and taking up the welt fabric as knitted, a welt wire, an intermediate fabric take-up connectible with the welt wire to take-up a fold of the welt fabric, a main take-up, means for supporting the main fabric take-up in position to receive the welt wire from said intervening take-up, and means actuated by the movement of said intermediate fabric take-up to render said main fabric take-up operative to take up the welt wire and fabric attached thereto.

18. In a flat knitting machine having welt turning mechanism associated therewith, the combination with instrumentalities arranged to set up and to take up the welt fabric as knitted, a support into which the welt wire can be laid prior to the time it is required, a main fabric take-up, an intervening fabric take-up, actuating means for operatively connecting said intervening take-up with the welt wire and for tensioning the welt wire against the fabric, and means for rendering said intervening take-up inoperative.

- and said main take-up operative to continue the take-up action upon the welt wire and fabric.
19. In a flat knitting machine having welt turning mechanism associated therewith, the combination with instrumentalities for setting up and for taking up the welt fabric as knitted, a welt wire, and a support into which the welt wire can be laid prior to the time it is required, fabric take-up means, means for imparting relative positioning movement to the support and take-up, means to engage the take-up with the welt wire and for thereafter moving the welt wire to take up a fold of welt fabric, and control means for rendering said last mentioned means operative to cause the welt wire to take up the fabric during the continued take-up action of said instrumentalities.
20. In a flat full-fashioned knitting machine arranged for knitting welt fabric, a fabric take-up device including a welt wire and take-up means connected thereto, a support into which the welt wire can be laid prior to the time that it is required, and means for relatively moving the support and take-up means to operatively connect the welt wire with the take-up means while held in said support, said support and welt wire having surfaces disposed transversely of said welt wire for operative engagement to control the lengthwise position of the welt wire.
21. In a flat full-fashioned knitting machine arranged for knitting welt fabric, a welt wire having formed therein annular groove portions, a welt-wire support comprising slotted supporting elements engaging with said annular grooves, a fabric take-up means including welt wire engageable with said grooves, and means for relatively moving the support and take-up means to operatively connect said welt wire engaging members with the groove portions of said welt wire and to take up the fabric.
22. In a flat knitting machine arranged for knitting welted fabric, the combination with a narrowing frame, of a welt wire, a fabric take-up connectible with the welt wire, means for supporting the take-up in position to receive the welt wire, and means controlled by movement of the narrowing frame to cause the take-up to take up the fabric.
23. In a flat knitting machine adapted for knitting welted fabrics, the combination with a narrowing frame, of a welt wire, a support for the welt wire and the narrowing frame, a fabric take-up connectible with the welt wire, means for supporting the fabric take-up in position to receive the welt wire from the support, and means controlled by a dipping movement of the narrowing frame to operatively connect the welt wire with the take-up.
24. In a flat knitting machine adapted for knitting welted fabrics, the combination with a narrowing frame, of a welt wire, a support for the welt wire on the narrowing frame, a fabric take-up connectible with the welt wire, means for supporting the fabric take-up in position to receive the welt wire from the support, means controlled by a dipping movement of the narrowing frame to operatively connect the welt wire with the take-up, and thereafter to cause the welt wire and take-up to take up the fabric.
25. In a flat knitting machine having a series of needles and welt turning mechanism associated therewith, the combination with a welt wire, of support on which the welt wire is located for subsequent engagement with the welt fabric, a fabric take-up comprising a pivotally mounted swinging
- support and welt wire engaging members thereon, tensioning means acting on said members to take up the fabric, and means for holding said fabric take-up in position to receive the welt wire from said first mentioned support.
26. In a flat knitting machine having a series of needles and welt turning mechanism associated therewith, the combination with a welt wire, of a support on which the welt wire is located for subsequent engagement with the welt fabric, a fabric take-up comprising a pivotally mounted swinging support, take-up members supported thereon for engagement with the welt wire, and latching means for retaining the welt wire in engagement with said take-up members, and means for imparting relative movement to the support and take-up to operatively connect the welt wire from the support with said take-up.
27. In a flat knitting machine having welt turning mechanism associated therewith, the combination with a welt wire, of a support on which the welt wire is located for subsequent engagement with the welt fabric, a fabric take-up, and means for imparting relative positioning movement to the take-up and support to operatively connect the take-up with the welt wire, and thereafter to remove the welt wire from said support.
28. In a multiple section flat full-fashioned knitting machine having a welt turning mechanism associated therewith, the combination with a welt wire for each section, of a support associated with each knitting section on which the welt wire is located, fabric take-up means associated with each knitting section, means for simultaneously imparting relative positioning movements to the take-ups and supports associated with the several knitting sections to operatively connect the take-ups with the welt wires, and means for simultaneously resetting said fabric take-up means in position for said relative positioning movements.
29. In a multiple section flat full-fashioned knitting machine having a welt turning mechanism associated therewith, the combination with a welt wire for each section, of a support associated with each knitting section on which the welt wire is located, fabric take-up means associated with each knitting section, positioning means for said take-ups including latching means, means for simultaneously imparting relative positioning movements to said supports and to said take-ups under the control of said latching means to operatively connect the take-up with the welt wire, and means for simultaneously resetting said fabric take-ups in latched position.
30. In a multiple section flat full-fashioned knitting machine having a welt turning mechanism associated therewith, the combination with a welt wire for each section, of a support associated with each knitting section on which the welt wire is located, fabric take-up means associated with each knitting section, locating means for said take-ups including latching means, means for simultaneously imparting relative positioning movement to the supports and take-ups under the control of said latching means to operatively connect the take-ups with the welt wires and for releasing said latching means to engage the welt wires against the fabric, and means for simultaneously resetting said fabric take-ups in latched position.
31. In a flat knitting machine arranged for mechanically turning the welt, a welt bar, a welt wire, a welt wire support mounted independently of and movable with relation to the welt bar into

which the welt wire can be laid in advance of the time it is required, fabric take-up means, and means for imparting relative positioning movement to the take-up and support to operatively connect the take-up with the welt wire to tension the fold of welt fabric.

32. In a flat knitting machine arranged for mechanically turning the welt, the combination with a needle series, a welt bar, and means for imparting a draw-off action to the welt bar to take up the fabric, a welt wire, a welt wire support movable with relation to the welt bar into which the welt wire can be laid in advance of the time it is required, fabric take-up means, and automatic means for imparting relative positioning movement to the take-up and support to operatively connect the take-up with the welt wire to tension the fold of welt fabric during continued take-up of the welt bar.

33. In a flat knitting machine arranged for mechanically turning the welt, a welt wire, a support on which the welt wire is positioned, fabric take-up means, and means for automatically imparting relative positioning movement to the take-up and support to operatively connect the take-up with the welt wire, said support and take-up being constructed and having the relative movement thereof arranged to cause the welt wire to be positively and continuously supported and controlled at all times by said support and take-up.

34. In a flat knitting machine arranged for mechanically turning the welt, a welt wire, a support on which the welt wire is positioned, fabric take-up means, means for automatically imparting relative positioning movement to the take-up and support to operatively connect the take-up with the welt wire, said support and take-up being constructed and having the relative movement thereof arranged to cause the welt wire to be positively and continuously supported and controlled at all times by said support and take-up, and including restraining means to prevent endwise movement of the welt wire in its support.

35. In a flat knitting machine arranged for mechanically turning the welt, a welt wire, a support on which the welt wire is positioned, fabric take-up means, and means for automatically imparting relative positioning movement to the take-up and support to operatively connect the take-up with the welt wire while held in said support, and restraining means associated with each of said support and take-up to prevent endwise movement of the welt wire.

36. In a flat knitting machine arranged for mechanically turning the welt, a welt wire, a sup-

port on which the welt wire is positioned, fabric take-up means including welt wire engaging hooks, and means for automatically imparting relative positioning movement to the take-up and support to operatively connect the take-up with the welt wire, said support and take-up being constructed and having the relative movement thereof arranged to cause the welt wire to be positively supported and controlled at all times by said support and take-up, and including restraining elements associated with the take-up hooks having a resilient action to hold the welt wire in the take-up hooks.

37. In a multiple section flat full-fashioned knitting machine having a welt turning mechanism associated therewith, the combination with a welt wire for each section, of a support associated with each knitting section on which the welt wire is located, fabric take-up means associated with each knitting section, means for simultaneously imparting relative positioning movements to the take-ups and supports associated with the several knitting sections to operatively connect the take-ups with the welt wires, said supports and take-ups being constructed and having the relative movement thereof arranged to cause the welt wires to be positively and continuously supported and controlled at all times by said supports and take-ups, and means for simultaneously resetting said fabric take-ups in position for said relative positioning movements.

38. In a flat knitting machine arranged for mechanically turning the welt, the combination with a welt wire, of a support into which the wire can be laid prior to the time that it is required, restraining means for holding the welt wire in its support, a fabric take-up, and means for imparting relative positioning movement to the take-up and support to operatively connect the take-up with the welt wire, and thereafter to remove the welt wire from the support.

39. In a flat knitting machine arranged for mechanically turning the welt, the combination with a welt wire, of a support into which the welt wire can be laid prior to the time when it is required, and movable to locate the welt wire in active position, restraining means for holding the welt wire in its support, a fabric take-up, and means for imparting relative positioning movement to the take-up and support to operatively connect the take-up with the welt wire, and thereafter to remove the welt wire from the support.

MAX C. MILLER.
